(57) **CLAIM**

The ornamental design for a multi-functional connector, as shown and described.

DESCRIPTION

FIG. 1 is a perspective view of a multi-functional connector showing our new design. The broken lines in FIG. 1 are included for the purpose of illustrating portions of the multi-functional connector that forms no part of the claimed design;

FIG. 2 is a front view of the multi-functional connector shown in FIG. 1. The broken lines in FIG. 2 are included for the purpose of illustrating portions of the multi-functional connector that forms no part of the claimed design;

FIG. 3 is a rear view of the multi-functional connector shown in FIG. 1. The broken lines in FIG. 3 are included for the purpose of illustrating portions of the multi-functional connector that forms no part of the claimed design;

FIG. 4 is a left side view of the multi-functional connector shown in FIG. 1;

FIG. 5 is a right side view of the multi-functional connector shown in FIG. 1;

FIG. 6 is a top view of multi-functional connector shown in FIG. 1;

FIG. 7 is a bottom view of the multi-functional connector shown in FIG. 1; and,

FIG. 8 is another perspective view of the multi-functional connector showing our new design. The broken lines in FIG. 8 are included for the purpose of illustrating portions of the multi-functional connector that forms no part of the claimed design.
